SOUND AND TELEVISION RECEIVER

Ralph S. Holmes, Haddonfield, N. J., assignor to
 Radio Corporation of America, a corporation
 of Delaware

Application June 28, 1934, Serial No. 732,759

14 Claims. (Cl. 250—9)

My invention relates to radio receivers and particularly to receivers adapted to receive picture signals and sound signals simultaneously.

In Carlson Patent 1,975,059, issued September 25, 1934, there is described a radio system in which picture signals and sound signals are transmitted simultaneously from a transmitter in order that a picture accompanied by speech or music may be received. The picture signals and sound signals are transmitted on separate carrier waves which are spaced apart a definite fixed amount in the frequency spectrum. All the transmitters in this system radiate two carrier waves, for the purpose mentioned, which are spaced apart the same definite fixed amount. The different transmitters transmit at different wave lengths, in accordance with usual practice, to permit selection at a receiver of the desired transmitting station.

In a radio system of the above-described type, the receiver includes a picture translating device such as a cathode-ray tube and a sound translating device such as a loud speaker. It has been found that, in tuning one of these receivers from one station to another, some very unpleasant effects are encountered. One results from the sound channel of the receiver being tuned for an instant to the incoming picture signal so as to produce a noise in the loud speaker. Another results from the picture channel of the receiver being tuned to the incoming sound signal for an instant so as to produce flashes of light on the fluorescent screen of the cathode-ray tube. Not only are these effects displeasing to a person operating the receiver, but they may result in injury to the apparatus, especially the cathode-ray tube.

An object of my invention is to provide an improved receiver for receiving picture and sound signals simultaneously.

More specifically, an object of my invention is to provide a receiver for use in a system of the above-mentioned type in which the aforesaid undesirable effects are avoided.

A further object of my invention is to provide a picture and sound receiver which will make a signal visible or audible only when the receiver is tuned to two carrier waves.

In a preferred embodiment of my invention I employ a superheterodyne receiver having an intermediate frequency channel through which picture signals are supplied to a cathode-ray tube and having another intermediate frequency channel through which sound signals are supplied to a loud speaker. A noise suppressor

circuit is provided which normally prevents signals from being impressed upon either the cathode-ray tube or the loud speaker. The noise suppressor circuit is so connected to the intermediate frequency channels that, when signals of the proper amplitude appear in both channels, the suppressor is released.

In one embodiment of my invention I take advantage of the fact that the frequency spacing between the carriers of the intermediate frequency signals is the same as the frequency spacing of the sound and picture carrier waves sent out from a transmitter. The two intermediate frequency carriers are heterodyned in a detector or mixer tube and the resulting beat frequency current is utilized to release the noise suppressor.

In another embodiment of my invention, instead of utilizing a beat frequency, use is made of an automatic volume control or A. V. C. circuit in each intermediate frequency channel. Each A. V. C. circuit is so connected to a noise suppressor circuit that the suppressor will be released only when signals of sufficient volume are being received in both channels.

Other objects, features and advantages of my invention will appear from the following description taken in connection with the accompanying drawings in which

Figure 1 is a diagram showing the frequency spacing of signals transmitted in a system of the above-described type and also showing certain selectivity characteristics of my improved receiver.

Fig. 2 is a diagram, similar to Fig. 1, showing the frequency spacing of a modified transmitting system.

Fig. 3 is a circuit diagram of an embodiment of my invention utilizing beat frequency control.

Fig. 4 is a circuit diagram of a modified form of the receiver shown in Fig. 3.

Figs. 5 and 6 are circuit diagrams of embodiments of my invention utilizing automatic volume control circuits for actuating the noise suppressor.

Referring to Fig. 1, two transmitter stations are indicated which are operating on adjacent channels and which are widely spaced apart geographically. Station No. 1 is represented as transmitting a picture signal on a 50,000 k. c. 50 carrier, the picture signal side bands having a width of 1000 k. c. This same station transmits sound signals on a 51,500 k. c. carrier which may have a side band width of 10 k. c.

Station No. 2, on an adjacent channel trans-

mits a picture signal on a 53,000 k. c. carrier and a sound signal on a 54,500 k. c. carrier.

The curve 1 shows the selectivity characteristic of the picture channel in a receiver of the type described in the above-mentioned Carlson patent, while the curve 3 shows the selectivity characteristic of the intermediate frequency sound channel in the same receiver. These curves are positioned with respect to the diagram for station No. 1 to indicate that the receiver is properly tuned to this station.

Consider now the operation of a receiver similar to the one shown in the Carlson patent, assuming the condition before the receiver was tuned to station No. 1: As the receiver is tuned towards stations No. 1 and No. 2, the intermediate frequency sound channel will first receive the signal from the picture carrier of 50,000 k. c. Under these conditions no energy is being received by the intermediate frequency picture channel, while the picture signal is appearing in the loud speaker as a disagreeable noise. Further tuning of the receiver tunes it accurately to station No. 1, as shown in the diagram.

Assume now that the receiver is tuned towards station No. 2: It will be apparent that before the receiver is properly tuned, the sound channel will receive the signal from the picture carrier of station No. 2 while the picture channel will be tuned to the sound carrier of station No. 1. As the signal from station No. 2 on the adjacent channel will be weak because of its geographic location, the picture signal noise in the loud speaker may not be very disturbing. The sound signal from station No. 1, however, will be a strong signal and will appear on the fluorescent screen of the cathode-ray tube as flashes of light which are annoying to an observer and which may injure the tube.

With respect to the system indicated in Fig. 2, there is the same condition of operation except that, because of the single side band transmission of the picture signals and the correspondingly closer frequency spacing of adjacent channels, the two intermediate frequency channels of the receiver may supply signals to the loud speaker and cathode-ray tube only when the receiver is properly tuned to the picture and sound signals from a single transmitting station.

Referring to the embodiment of my invention showing in Fig. 3, it comprises a superheterodyne receiver having a radio frequency selecting circuit 5, a first detector 7 and a tunable oscillator 9. As described in the above-mentioned Carlson patent, the selecting circuit 5 has a pass range wide enough to permit the passage of both the picture and sound signals from a single transmitting station. At the same time the selectivity is sufficient to separate the signals from one transmitting station from those from a different station. Preferably, the variable condensers or other tuning elements of the selecting circuit and of the oscillator are connected to a common control knob 11 to permit simultaneous tuning of both selecting circuit and oscillator.

The oscillator output beats with an incoming signal in the first detector 7 to produce an intermediate frequency picture signal which is selected and amplified by a tuned intermediate frequency amplifier 13 and to produce an intermediate frequency sound signal which is selected and amplified by a tuned intermediate frequency amplifier 15. In the particular example being described, the intermediate frequency picture amplifier 13 is tuned to 11,000 k. c. while the

intermediate frequency sound amplifier 15 is tuned to 9,500 k. c. The selecting circuits in both amplifiers are of the band-pass type, as indicated by the curves 1 and 3 in Figs. 1 and 2.

The output of the picture amplifier 13 is impressed upon an amplifier tube 17 which may be of the four-electrode type comprising a cathode 19, a control grid 21, screen grid 23 and an anode 25. The signal appearing in the plate circuit of the tube 17 is impressed upon a second detector 27 which may be of the diode type whereby the picture signal appears across a resistor 29 in the diode circuit.

It will be understood that the picture signal appearing across resistor 29 includes the synchronizing impulses or signals. The picture signal is impressed upon an amplifier 31 which includes circuits for separating the picture signal proper from the synchronizing signals. The output of the amplifier 31 is applied to the control grid 33 and to the deflecting devices 34 and 35 of a cathode-ray receiver tube 36. The tube illustrated is of the type having a first anode 37, a second anode 39 and a fluorescent screen 41 at the end of the tube.

The output of the sound amplifier 15 is impressed upon an amplifier tube 43 which may be of the screen grid type comprising a cathode 45, a control grid 47, a screen grid 49 and an anode 51. The sound signal appearing in the plate circuit of the amplifier tube 43 is impressed upon a second detector 53 which may be of the diode type whereby the sound signal appears across a resistor 55 in the diode circuit. The sound signal is amplified by an amplifier 57 and supplied to a loud speaker 59.

In accordance with my invention, the amplifier tubes 43 and 17 are normally so biased that they will not amplify a signal. The circuit which maintains this high negative bias on the amplifier tubes comprises a vacuum tube 61 having a cathode 63, a control grid 65, an anode 67 and a rectifier electrode 69. A tuned circuit 71, which will be more fully described hereinafter and which comprises an inductance coil 73 shunted by a condenser 75, is connected at its upper terminal to the rectifier electrode 69 while it is connected at its lower terminal through a resistor 77 to the cathode 63. The control grid 65 is connected to the end of the resistor 77 which is connected to the lower terminal of the tuned circuit 71.

The cathode 63 of the tube 61 is connected through a resistor 79 to ground while the anode 67 is connected to a suitable source of positive potential whereby there is a flow of plate current through the resistor 79 so long as the control grid 65 is not too negative with respect to the cathode 63.

The cathodes of the amplifier tubes 43 and 17 are connected through conductors 81 and 83 to the cathode end of the resistor 79 whereby they are held positive with respect to ground when plate current is flowing therethrough. It will be seen, therefore, that when no signal is being impressed upon the tuned circuit 71 there is no flow of current through the diode circuit resistor 77, the control grid 65 is at cathode potential and the flow of plate current through the resistor 79 holds the cathodes 45 and 19 at a positive potential with respect to ground.

By making the cathodes 45 and 19 of the amplifier tubes 43 and 17 positive with respect to ground, the control grids 47 and 21 of these tubes are put at a negative potential with re-

pect to their cathodes since they are connected to ground through their tuned input circuits. The circuit is so adjusted that when the grid 65 of the noise suppressor tube 61 is at cathode potential, the flow of plate current through the resistor 79 makes the control grids of the amplifier tubes 43 and 17 so negative that these tubes are ineffective to amplify either picture or sound signals.

10 The release of the suppressor is effected in response to signals appearing in both the sound amplifier 15 and picture amplifier 13 by means of a mixer or detector tube 85 which comprises a cathode 87, a control grid 89, a second control 15 grid 91, a screen grid 93 and an anode 95. The cathode 87 is connected to ground through a source of biasing potential such as a battery 97 whereby the control grids 89 and 91 are biased to a suitable negative potential through the resistors 99 and 101, respectively.

10 The control grid 89 is connected through a coupling condenser 103 and a conductor 105 to the output circuit of the sound amplifier 15 while the control grid 91 is connected through 25 a coupling condenser 107 and a conductor 109 to the output circuit of the picture amplifier 13. The anode 95 of the mixer tube is supplied with positive potential from a suitable source through a tuned circuit 111 which is coupled to the tuned 30 input circuit 71 of the noise suppressor tube 61. The two coupled tuned circuits 111 and 71 form a circuit which is sharply tuned to 1500 k. c., which is the beat frequency between the intermediate frequency picture signal and the intermediate frequency sound signal.

When the receiver is so tuned to a station that signals appear in the output circuits of the sound and picture intermediate frequency amplifiers, a beat frequency is produced in the tuned 40 output circuit of the mixer tube 85 which frequency is selected by the tuned circuit and impressed across the rectifier electrode 69 and the cathode 63. As a result, current flows through the rectifier resistor 77 in such a direction as 45 to make the control grid 65 negative with respect to the cathode 63. This flow of current through the resistor 77 is caused to have a substantial steady value by shunting a filter condenser 113 thereacross. If the picture and 50 sound signals have a sufficient amplitude, the grid 65 of the suppressor tube is made so negative that the current flow through the plate resistor 79 is greatly reduced whereby the high negative bias is removed from the control grids 21 and 47 of the amplifier tubes 17 and 43 and these tubes function to amplify the picture and sound signals so that they appear at the cathode-ray tube 36 and loud speaker 58, respectively.

From the foregoing description, it will be understood that if the picture channel of the receiver is tuned to the sound signal or if the sound channel of the receiver is tuned to the picture signal, no signal will be impressed upon either the cathode-ray tube or the loud speaker. 60 With the transmitting system indicated in Fig. 1 there is a possible exception to this statement which would seldom occur in practice. If a receiver happens to be so located that it receives signals of approximately equal strength from 65 two stations, such as stations No. 1 and No. 2, which are on adjacent channels, it is possible to get signals on the cathode-ray tube and in the loud speaker by receiving a sound signal from one station and a picture signal from the other 70 station.

With the transmitting system indicated in Fig. 2, there is no condition under which signals will appear at the cathode-ray tube and loud speaker unless the receiver is properly tuned, since it must be tuned accurately to a station in order 5 to obtain the 1500 k. c. beat note.

Under certain conditions either the sound signal or the picture signal arriving at a receiver from a transmitter may be weak or of poor quality while the other signal from that transmitter 10 is of good quality. Or, a station may transmit a picture signal unaccompanied by a sound signal or vice versa. Therefore, in order that a single signal may be received from a transmitter 15 it is desirable that means be provided for making the suppressor circuit of the receiver inoperative at will.

Referring to Fig. 3, this may be accomplished by providing a switch 92 in the plate circuit of the suppressor tube 61. The receiver will normally be operated with the switch 92 closed. If it is known that a certain station should be transmitting a program which may be either a picture or sound alone, the receiver will be tuned to that station while the switch 92 is closed. 20 Then the switch 92 will be opened to permit reception of the single signal.

In a similar manner, the suppressor for the receiver shown in Fig. 6 may be rendered ineffective by opening a switch 286 in the plate 30 circuit of the suppressor tube 279.

In Fig. 4 there is shown a modification of the circuit shown in Fig. 3. In the two figures, like parts are indicated by the same reference numerals. The difference between the two circuits is 35 the manner in which the control or biasing voltage is supplied from the noise suppressor tube 61 to the amplifier tubes 43 and 17.

In the modification shown in Fig. 4 the cathodes 45 and 19 of the amplifier tubes 43 and 17 40 are connected to ground while the control grids 47 and 21 are connected through conductors 117 and 119 and through a filter resistor 121 to a biasing resistor 123 in the noise suppressor circuit. The bias resistor 123 is included in the 45 plate circuit of the noise suppressor tube 61 in series with the secondary 125 of a transformer 127 which supplies voltage to the plate 61. It will be understood that a battery may be substituted in the plate circuit for the alternating 50 current supply if desired. It will be seen that when plate current flows through the biasing resistor 123, the control grids 47 and 21 of the amplifier tubes 43 and 17 are biased negatively with respect to their cathodes. When the plate 55 of the noise suppressor tube 61 is supplied from an alternating current source as shown, it is preferred to connect a filter condenser 129 between one end of the filter resistor 123 and 60 ground in order to supply a substantially constant bias voltage to the amplifier tubes 43 and 17.

The operation of the circuit is substantially the same as that of the circuit shown in Fig. 3. If one of the intermediate frequency amplifier 65 channels is not receiving signal energy, no beat note appears in the output circuit of the mixer tube 85 and the flow of current through the biasing resistor 123 maintains the amplifier tubes 43 and 17 biased so negatively that neither one 70 of them will amplify a signal impressed upon it. On the other hand, when both intermediate frequency channels are receiving energy, a 1500 k. c. beat note appears in the output circuit of the mixer tube 85 and the flow of current 75

through the biasing resistor 123 is reduced to a value which permits the two amplifier tubes 43 and 17 to amplify the signals impressed upon them.

5 Referring to Fig. 5, there is shown an embodiment of my invention in which a noise suppressor circuit is controlled by means of automatic volume control circuits. The radio frequency amplifier or selecting circuit, the first 10 detector, and the oscillator superheterodyne receiver are indicated at 131. The output circuit of the first detector is coupled to the input circuit of an intermediate frequency sound amplifier 133 through a secondary winding 135 of a 15 transformer 137 and to the intermediate frequency picture amplifier 139 through another secondary winding 141 of the transformer 137.

In order to simplify the drawings, only the 20 circuit of the first tube in each intermediate frequency amplifier is shown. The input circuit of the first tube 143 of the sound amplifier 133 includes the secondary winding 135 which is tuned to the sound intermediate frequency by a condenser 145. The cathode 147 of the tube 25 143 is maintained at a positive potential with respect to ground by means of a self biasing resistor 149 which is shunted by the usual by-pass condenser 151.

The gain of the amplifier tube 143, as well as 30 the gain of other intermediate frequency amplifier tubes (not shown), is controlled automatically by varying the bias on its control grid 153 through a conductor 154 to the output circuit of an automatic volume control tube 155.

35 The output circuit of the sound amplifier 133 is coupled through a tuned intermediate frequency transformer 157 to an amplifier tube 159, which in turn has its output circuit coupled to a second detector 161. The amplifier tube 159 may be of the screen grid type having its cathode 163 maintained at a positive potential with respect to ground by means of a self-bias resistor 165 and having its control grid 167 connected through the secondary of the 40 transformer 157 and through a conductor 169 to the noise suppressor circuit which will be described later. In the particular embodiment illustrated, the second detector 161 is of the diode type and includes in its circuit a resistor 171 45 across which the sound signals appear.

The picture amplifier 139 is similar to the sound amplifier and includes a first amplifier tube 173 which has its cathode 175 maintained at a positive potential with respect to ground 50 by means of a self-bias resistor 177. The control grid 179 of this amplifier tube, as well as the control grids of other intermediate frequency amplifier tubes (not shown), is connected through a conductor 181 to the output circuit of 55 an automatic volume control tube 183.

60 The output circuit of the picture amplifier 139 is coupled through a tuned intermediate frequency transformer 185 to an amplifier tube 187 which has its output circuit coupled to a second detector 189. As in the sound channel, the second detector 189 may be of the diode type having a resistor 191 in its circuit across which the picture signals appear.

65 Referring now to the automatic volume control circuit for the sound channel, it comprises the amplifier tube 155 which may be of the screen grid type having a cathode 193, a control grid 195, a screen grid 197 and an anode 199. The tube 155 also includes a rectifier electrode 201 70 which is positioned adjacent to a small section

of the cathode 193. The cathode 193 is held positive with respect to ground by means of a self-biasing resistor 203 which is shunted by a suitable by-pass condenser 205.

The control grid 195 is connected through a 5 resistor 207 to a point on the self-biasing resistor 203 for maintaining the tube 155 biased at such a value that it will function efficiently as an amplifier. The upper portion of the self-biasing resistor 203 is preferably shunted by 10 another by-pass condenser 209. The plate 199 and the screen grid 197 are supplied with positive potentials from any suitable source.

The input circuit of the tube 155 is coupled through a coupling condenser 211 to the output 15 circuit of the sound amplifier 133. Therefore, when an incoming signal is received, an amplified high frequency current appears in the plate circuit of the amplifier tube 155. This current is impressed upon the rectifier section of the 20 tube 155 through a sharply tuned transformer 213. The rectifier circuit, which includes a resistor 215, may be traced from the rectifier plate 201 through the secondary 217 of the transformer 213 and the resistor 215 to ground and 25 through ground and the self-biasing resistor 203 to the cathode 193.

It will be seen that as soon as a sound signal 30 appears in the output of the sound amplifier 133, current is caused to flow through the rectifier circuit in such a direction as to make the upper end of the resistor 215 negative with respect to ground. It is to this end of the resistor 215 that the conductor 154 from the control electrodes of 35 the intermediate frequency amplifier tubes is connected. The connection is made through a filter resistor 219 which has filter condenser 221 connected between one end and ground. A filter condenser 223 is also connected across the resistor 215. It will be understood that as the 40 strength of the signal increases the upper end of the resistor becomes more negative, whereby a more negative bias is applied to the amplifier tube 143 to reduce the gain.

The A. V. C. circuit for the picture channel 45 is the same as the A. V. C. circuit described above and includes the amplifier tube 183 which has its input circuit coupled to the output circuit of the picture amplifier 139 through a coupling condenser 225 and its output circuit coupled through a sharply tuned transformer 227 to a rectifier section of the tube. The circuit of the rectifier section includes a resistor 229 which is so connected that its upper end becomes increasingly negative as the strength of the picture 55 signal increases. The conductor 181 from the control grids of the intermediate frequency amplifier tubes is connected through a filter resistor 231 to the upper end of the resistor 229.

In accordance with my invention, the sound 60 channel is provided with a noise suppressor tube 233 while the picture channel is provided with a noise suppressor tube 235. The noise suppressor tubes may be of the screen grid type. The tube 233 comprises a cathode 237, a control grid 239, a 65 screen grid 241, and a plate 243. The control grid 239 is connected through a filter resistor 245 to the upper end of the volume control resistor 215. The cathode 237 may be connected to ground through a battery 247 or another source of 70 biasing potential for maintaining the cathode negative with respect to ground for providing the desired delay in the noise suppressor action. A filter condenser 249 is connected between the grid end of the filter resistor 245 and ground. 75

Since the bias voltage supplied by the battery 247 opposes the voltage drop across the volume control resistor 215, the control grid 239 will not become negative until the amplitude of the incoming signal reaches a predetermined value. Until the control grid 239 reaches a certain negative value, current flows through a resistor 250 in the plate circuit of the tube 233, the plate potential being supplied through a transformer 10 251 or a battery (not shown). So long as plate current flows through the resistor 250, its upper end is negative with respect to ground.

The control grid 161 of the amplifier tube 159 is connected through the conductor 169 and 15 through a filter resistor 253 to the upper end of the plate resistor 250 whereby the amplifier tube 159 is biased substantially to cut-off until the amplitude of an incoming signal reaches a value sufficient to put a high negative bias on the 20 control grid of the noise suppressor tube 233. The usual filter condenser 255 is connected between the grid end of the filter resistor 253 and ground.

In the picture channel, the noise suppressor 25 circuit is the same as that in the sound channel. The input circuit of the tube 235 is connected across the volume control resistor 229 whereby the tube 235 is biased approximately to cut-off when an incoming signal reaches a predetermined 30 amplitude. Until the signal reaches this amplitude, current flows in the plate circuit of the tube 235 through the plate resistor 250 which is common to the plate circuits of both suppressor tubes. Likewise, both plate circuits are supplied with plate voltage from the same alternating current source.

The control grid of the amplifier tube 187 is connected through the secondary of transformer 185 and through a conductor 257 to the grid end 40 of the filter resistor 253, whereby the tube 187 is rendered ineffective to amplify a signal while there is a flow of plate current through the resistor 250.

The suppressor circuit is so adjusted that if 45 the resistor 250 has plate current flowing therethrough from either the suppressor tube 233 or the suppressor tube 235, both amplifier tube 159 and amplifier tube 187 will be biased so negatively that they are ineffective to amplify a signal. Therefore, if only one of the signal channels is receiving a signal, the noise suppressor of the other channel is preventing a signal from being applied to either the loud speaker or to the cathode-ray tube. For example, if the sound 50 channel is tuned to the picture signal the picture signal will not appear as noise in the loud speaker because the noise suppressor circuit in the picture channel will be holding the amplifier tube in the sound channel negatively biased to 60 a high value.

The suppressor tubes 233 and 235 should have their voltages adjusted to give quicker cut-off than the intermediate frequency amplifier tubes which are controlled directly from the A. V. C. 65 circuit. It has been found that RCA-57 type tubes are satisfactory as suppressor tubes when RCA-58 type tubes are being used as the intermediate frequency amplifier tubes.

In order to insure that the receiver will be 70 tuned exactly to a desired station before the noise suppressor releases, the transformers 213 and 227 may be tuned to have an over-all selectivity (together with the preceding tuned transformers) shown by the curves 254 and 256, 75 respectively, in Figs. 1 and 2. In some cases it

may be preferred to tune the transformers 213 and 227 no more sharply than each of the preceding intermediate frequency transformers. It will be seen, however, that in any case the selectivity of the sound channel insures that the picture channels will be tuned with reasonable accuracy to the picture signal before the noise suppressor releases. 5

In Fig. 6, I have shown a simplified form of noise suppressor circuit in which the A. V. C. 10 action is utilized. In Figs. 5 and 6 like parts are indicated by the same reference numerals. In this modification, the second detectors 161 and 189 are coupled directly to the output circuits of the amplifiers 133 and 139, respectively, and the 15 A. V. C. bias for the intermediate frequency amplifier tubes is obtained from the resistor in the diode circuit.

Sound signals appearing across the resistor 171 in the circuit of the diode 161 are supplied 20 through a coupling condenser 259 to the input circuit of an audio frequency amplifier tube 261. The tube may be of the three electrode type comprising a cathode 263, a control grid 265, and a plate 267.

In the picture channel, the picture signals appearing across the resistor 191 in the second detector circuit are supplied through a coupling condenser 269 to a picture amplifier tube 271 30 which may be of the three electrode type comprising a cathode 273, a control grid 275, and a plate 277.

Signals are prevented from appearing at the loud speaker and cathode-ray tube by biasing the grids of the sound amplifier tube 261 and the picture amplifier tube 271 to a high negative value. This is accomplished by means of a circuit comprising a suppressor tube 279 which functions as two separate amplifier tubes. It includes one set of electrodes consisting of a 40 cathode 281, a control grid 283, and a plate 285, and a second set of electrodes consisting of a cathode 287, a control grid 289 and a plate 291. The cathodes 281 and 287 are connected to ground while the anodes 285 and 291 are connected together and supplied through a transformer 293 with potential from an alternating current source or from a direct current source (not shown). The plate circuit of the tube 279 50 includes a resistor 295 for supplying the control bias to the audio amplifier tube 261 and picture amplifier tube 271.

The control electrode 289 of the tube 279 is connected through a filter resistor 297 to that end of the second detector resistor 171 which 55 supplies the A. V. C. bias for the tubes in amplifier 133. The other control grid 283 of the tube 279 is connected through a filter resistor 299 to that end of the second detector resistor 191 which supplies A. V. C. bias for the tubes in 60 amplifier 139. It will be seen that if there is no signal in one of the signal channels, one of the control grids of the suppressor tube 279 will be substantially at ground potential whereby there will be a flow of plate current through the plate 65 resistor 295 to so bias the amplifier tubes 261 and 271 that they are ineffective to amplify a signal. On the other hand, if the receiver is properly tuned to a station, the sound signal will cause a high negative bias to be put on the 70 control grid 289 of the noise suppressor tube 279 while the picture signal will cause a high negative bias to be put on the other control grid 283 of the noise suppressor tube 279 and the flow of current through the plate resistor 75

295 will be so reduced in value that the amplifier tubes 261 and 271 will be properly biased for amplifying the sound and picture signals.

From the foregoing description it will be understood that by applying my invention to a combined television and sound receiver, the receiver is made inoperative when either the television carrier wave or the sound carrier wave is not being received or when either one of them 10 is so reduced in value that the reception would not be satisfactory. The receiver is operative to render a signal visible or audible only when the receiver is properly tuned to two carrier waves having a predetermined frequency spacing.

15 Various other modifications may be made in my invention without departing from the spirit and scope thereof and I desire, therefore, that only such limitations shall be placed thereon 20 as are necessitated by the prior art and are set forth in the appended claims.

I claim as my invention:

1. In a radio receiver for the simultaneous reception of two carrier waves, each of which is 25 modulated by a different signal, two translating devices, and means responsive only to the reception of both of said carrier waves for impressing one of said signals upon one of said translating devices.

30 2. A receiver according to claim 1 characterized in that one of said translating devices is a loud speaker and the other translating device a cathode-ray tube.

35 3. In a radio receiver for receiving simultaneously two modulated carrier waves having a predetermined frequency spacing, a tunable selecting circuit, two translating devices, means for demodulating said carrier waves whereby 40 two signals are produced, circuit connections between said demodulating devices and said translating devices whereby one of said signals may be impressed upon one of said translating devices and the other of said signals may be impressed upon the other of said translating 45 devices, and means responsive only to the reception of both of said carrier waves for impressing one of said signals upon one of said translating devices.

40 4. In a receiver for receiving simultaneously one carrier wave modulated by a picture signal and another carrier wave modulated by a sound signal, a tunable selecting circuit, a cathode-ray tube, a loud speaker, means for demodulating said carrier waves to produce a picture signal 55 and a sound signal, means whereby said picture signal and said sound signal may be impressed upon said cathode-ray tube and loud speaker, respectively and means responsive only to the reception of both of said carrier waves for impressing one of said signals upon said loud speaker.

5. A radio receiver comprising a radio frequency selecting circuit adapted to select a plurality of modulated carrier waves, means for 65 heterodyning said carrier waves to a plurality of intermediate frequency signals, means for demodulating one of said intermediate frequency signals to produce a certain signal, means for impressing said certain signal upon a translating 70 device, means for demodulating another of said intermediate frequency signals to produce a different signal, means for impressing said different signal upon a second translating device, and means for preventing either said certain signal 75 or said different signal from being impressed

upon said translating devices so long as said selecting circuit is not tuned to a plurality of said carrier waves.

6. A receiver according to claim 5 characterized in that means is provided for making said last means ineffective at the will of the operator.

7. In a receiver for the simultaneous reception of two carrier waves, each of which is modulated by a signal, a plurality of translating devices, means for heterodyning one of said carrier waves with the other of said carrier waves to produce a beat frequency, and means responsive to the production of said beat frequency for impressing said signals upon said translating devices.

10 15 8. A receiver according to claim 7 characterized in that one of said translating devices is a cathode-ray tube for the reception of picture signals.

9. In a receiver for the simultaneous reception of two carrier waves, at least one of which is modulated by a signal, means for heterodyning said carrier waves to two intermediate frequency signals, means for heterodyning one of said intermediate frequency signals by the other 25 of said intermediate frequency signals to produce a beat frequency, a translating device, and means for impressing said signal upon said translating device in response to the production of said beat frequency.

30 35 10. A receiver according to claim 9 characterized in that said signal is supplied to said translating device through an amplifier, and further characterized in that said last means includes means for maintaining said amplifier substantially ineffective to amplify so long as said beat frequency is not being produced.

40 45 11. In a receiver for the reception of at least two carrier waves, each modulated by a signal, means for selecting said carrier waves, means for converting said modulated carrier waves to intermediate frequency signals, an amplifier tuned to one of said intermediate frequency signals, an amplifier tuned to another of said intermediate frequency signals, a plurality of translating devices, means for transferring signal energy from one of said amplifiers to one of said translating devices, means for transferring signal energy from said second amplifier to another of said translating devices, and means for making 50 said two last-named means ineffective in response to the signal strength in either of said amplifiers falling below a predetermined value.

55 12. A receiver according to claim 11 characterized in that one of said amplifiers is tuned comparatively sharply to receive sound signals while the second of said amplifiers is tuned comparatively broadly to receive picture signals, and further characterized in that said one translating device is a loud speaker while said second translating device is a cathode-ray tube.

60 65 13. A receiver comprising a broadly tuned radio frequency selecting circuit, a heterodyne oscillator and detector, a sharply tuned intermediate frequency amplifier, a broadly tuned intermediate frequency amplifier, an automatic volume control operating in conjunction with each intermediate amplifier in such a manner that the output of each amplifier remains substantially constant under proper receiving conditions, and means controlled by both automatic volume controls for rendering a subsequent amplifier tube in each channel inoperative when a signal of insufficient strength to operate the automatic 70 75

volume controls is impressed upon either intermediate amplifier.

14. A receiver comprising a broadly tuned radio frequency selecting circuit, a heterodyne oscillator and detector, a sharply tuned intermediate frequency amplifier, an automatic volume control operating in conjunction with said intermediate frequency amplifier to maintain its output substantially constant when a signal of sufficient intensity is being received, a second intermediate frequency amplifier having a relatively broad selectivity characteristic tuned to a slightly different frequency than the first intermediate amplifier, an automatic volume control operating in conjunction with the second intermediate frequency amplifier to maintain its output substantially constant when a signal of suffi-

cient intensity is being received, said second automatic volume control having a selectivity characteristic such that it will operate over only a substantially small band of the frequencies passed by the second intermediate amplifier, a 5 demodulating device following each intermediate amplifier, an amplifier following each demodulator, a utilization device following each of the last mentioned amplifiers, and means responsive to the outputs of both automatic volume controls 10 for preventing any signal voltage from reaching either utilization device when a signal of insufficient strength or of improper frequency to operate the automatic volume controls is impressed upon either intermediate frequency amplifier. 15

RALPH S. HOLMES.
